UNITED STATES PATENT OFFICE

137,686

DESIGN FOR A TOY BOOK

Heinz W. Maienthau, Chicago, Ill., assignor to Sears, Roebuck and Co., Chicago, Ill., a corporation of New York

Application February 25, 1943, Serial No. 109,623

Term of patent 3½ years

(Cl. D6—2)

To all whom it may concern:

Be it known that I, Heinz W. Maienthau, a citizen of the United States of America and a resident of Chicago, in the county of Cook and State of Illinois, have invented a new, original, and ornamental Design for a Toy Book, of which the following is a specification, reference being had to the accompanying drawing, forming a part thereof.

Fig. 1 is a top plan view of a toy book embodying my new design;

Fig. 2 is a right side elevational view of the same, partly broken away to show details;

Fig. 3 is a front elevational view of the same with the book leaves spread apart;

Fig. 4 is a bottom plan view of Fig. 3;

Fig. 5 is a perspective view of the same.

I claim:

The ornamental design for a toy book, substantially as shown.

HEINZ W. MAIENTHAU.
